[57]

CLAIMThe ornamental design for a catheter cover, as shown and
described.**DESCRIPTION**FIG. 1 is a perspective view of a catheter cover showing our
new design;

FIG. 2 is a front end elevational view thereof;

FIG. 3 is a rear end elevational view thereof;

FIG. 4 is a top plan view thereof;

FIG. 5 is a side elevational view thereof;

FIG. 6 is a bottom plan view thereof; and,

FIG. 7 is a perspective view thereof showing its relationship
to a catheter introducer needle assembly, which is in broken
lines and forms no part of the claimed invention.**1 Claim, 3 Drawing Sheets**FIG-1
